UNITED STATES PATENT OFFICE.

CHARLES A. HUSSEY, OF NEW YORK, N. Y., ASSIGNOR TO THE HUSSEY ELECTRIC COMPANY, OF SAME PLACE.

DYNAMO-ELECTRIC MACHINE.

SPECIFICATION forming part of Letters Patent No. 253,387, dated February 7, 1882.

Application filed August 31, 1881. (No model.)

To all whom it may concern:

Be it known that I, CHARLES A. HUSSEY, of New York, in the county and State of New York, have invented certain new and useful 5 Improvements in Dynamo-Electric Machines, of which the following is a specification.

My improvements consist in a field-magnet for a dynamo-electric machine, composed of corresponding arc-shaped principal or main 10 portions and intervening portions made continuous with said principal or main portions wound with wire and sufficiently offset from the main arc-shaped portions that when a proper quantity of wire is wound on them it 15 will on the interior be approximately coincident with the interior surfaces of the main arc-shaped portions.

The improvements further consist in the combination, with such a field-magnet, of an 20 armature composed of a core wound lengthwise with wire arranged within the same. This armature, when rotated, will travel before the poles or consequent points, as also before the entire length of the field-magnet, and hence it 25 will move through the entire field of force. The dynamo-electric machine comprising such a field-magnet will be cheaper, more compact, and lighter than one made in the ordinary way, because it will have a lighter and less 30 bulky core and less wire thereon.

In the accompanying drawings, Figure 1 is a perspective view of a dynamo-electric machine embodying my improvements. Fig. 2 is a transverse section of the same. Fig. 3 is an 35 edge view, on a smaller scale, of the core of the field-magnet and wire wound thereon. Fig. 4 is a perspective view illustrative of the winding of wire on the field-magnet, and Fig. 5 represents an end view of the armature-core 40 and appurtenances.

Similar letters of reference designate corresponding parts in all the figures.

A A' designate the core of the field-magnet, which consists of opposite corresponding principal or main portions, A, and intervening portions A', made continuous with the principal or main portions wound with insulated wire A², and sufficiently offset that the interior surface of the wire will be approximately coinci-

dent with the interior of the main portions of 50 the magnet. The intervening portions A' may be arc-shaped, or they may be perfectly flat and straight, as shown. This core may be of cast-iron or other suitable material. The insulated wire is wound on them, so as to form 55 poles or consequent points of the main portions A of the core of the magnet. The method of winding the wire is fully illustrated in Fig. 3. If desirable, however, the wire may be wound in reverse directions from the center 60 toward each end of the intervening portions A' of the magnet-core. The wire may be retained in place laterally by pins A³. As here shown, the field-magnet is arranged so that one of the intervening portions A' is at the 65 top or uppermost portion, and the other is at the bottom or lowermost portion of the said field-magnet, and it is supported by means of two feet, A⁴, secured to its exterior and to a base-piece, B, by screws or bolts a. 70

C C' designate an armature consisting of a metal core, C, and insulated wire C', wound thereon. The core consists of a number of thin plates of wrought-iron or other suitable material. Its shape is that of a number of 75 coincident arcs of a circle and a number of intervening coincident and concentric arcs of a circle of larger radii connected to the former by approximately radial portions. The construction of the armature-core is clearly shown 80 in Fig. 5. The insulated wire is wound over the smaller arcs and through the hollow interior, and when in place its exterior is approximately coincident with the exterior of the larger arcs. The coils of wire thus produced extend in the 85 same direction, and the inner end of one is connected with the outer end of the next throughout the armature, loops being thus formed which are connected by leading-wires C² with the plates of a commutator, D, mounted 90 on the exterior of the shaft C³ of the armature. The plates of which the armature-core is composed may be connected to spiders, which in turn are connected with a hub fitting the said shaft. This shaft is supported in bearings in 95 spiders E, which are secured by screws b to the ends or edges of the core of the field-magnet. The leading-wires C² pass through a

bushing, F, of insulating material, which is affixed to the shaft C³ and fits in one of the bearings in the spiders E.

5 G designates lubricators for the bearings in the spiders E.

The shaft C³ may be driven by means of a belt applied to a pulley, C⁴, mounted on said shaft.

10 G' G² designate brushes, which are supported in posts G³ and bear on the commutator. The posts G³ are affixed to an annular plate, H, but are insulated therefrom by washers or gaskets of insulating material. The annular plate H is provided with concentric slots e, through 15 which pass screws f, which screw into arms I, which are mounted on the spider E which is nearer to the commutator. By loosening these screws the plate H may be turned to adjust both the brushes in unison, and by subsequently tightening the screws the brushes may be secured in the position to which they are 20 adjusted.

One end of the wire of the field-magnet—namely, the end g, Fig. 2—is connected to a 25 binding-post, J, and the other end of the wire—namely, the end h, Fig. 2—is connected to the brush G². The brush G' is connected by a wire to the binding-post J'. These binding-posts, when the base-piece B is made of metal, 30 are insulated therefrom by washers or gaskets of insulating material. Wires K lead from the binding-posts J J' to conduct off the current of electricity generated by the machine.

The armature, when rotated, travels before 35 the poles or consequent points, as also the whole length of the field-magnet. Hence it moves throughout the entire field of force and very powerful electric currents are generated.

As the core of the field-magnet is very light and the amount of wire used is very small, I 40 produce by my improvements a machine which, for its power, is exceedingly cheap, light, and compact.

What I claim as my invention, and desire to secure by Letters Patent, is— 45

1. A field-magnet for a dynamo-electric machine, composed of corresponding principal or main arc-shaped portions and intervening portions made continuous with the said principal or main portions wound with wire and sufficiently offset from the main arc-shaped portions that when a proper quantity of wire is wound on them it will on the interior be approximately coincident with the interior surface of the main arc-shaped portions, substan- 50 tially as specified.

2. The field-magnet composed of the corresponding arc-shaped portions A, the intervening offset portions made continuous with said arc-shaped portions A, the wire A², and the 60 pins A³, substantially as specified.

3. In a dynamo-electric machine, the combination, with a field-magnet composed of corresponding principal or main arc-shaped portions and intervening offset portions made 65 continuous with said principal or main portions wound with wire, of an armature arranged to rotate within the same and consisting of a core wound longitudinally with wire, substantially as specified.

C. A. HUSSEY.
